ELECTROLUMINESCENT PANEL FOR A COIN OPERATED AMUSEMENT DEVICE

Frederick A. Hurley, 10911 NE. 10th Ave., Miami, Fla.

Filed Oct. 26, 1964, Ser. No. 82,319

Term of patent 14 years

(Cl. D34—5)

The figure is a perspective view of an "electroluminescent panel for a coin operated amusement device" showing my new design.

The essential features of my design reside in the portions shown in full lines with the horseshoes as well as the several arm positions on the figure being electroluminescent and indicating by successive illumination thereof, the throwing and flight of a horseshoe.

I claim:

The ornamental design for an electroluminescent panel for a coin operated amusement device, as shown and described.
